UNITED STATES PATENT OFFICE.

ANTONINA RYBICKY, OF NEW LONDON, CONNECTICUT.

SANITARY CUSPIDOR.

Application filed November 16, 1922. Serial No. 601,246.

To all whom it may concern:

Be it known that I, ANTONINA RYBICKY, a citizen of Poland, residing at New London, in the county of New London and State of Connecticut, have invented certain new and useful Improvements in Sanitary Cuspidors, of which the following is a specification.

This invention relates to cuspidors, and it has for a general object to provide a novel type of cuspidor having its mouth normally closed to prevent the escape of odors, and which can be quickly and easily opened by the user.

More specifically speaking the invention has for an object to provide a cuspidor having a hinged cover operable by a foot pedal, means being provided for varying the extent to which the cover is swung back by depression of the foot pedal.

For further comprehension of the invention, and of the objects and advantages thereof, reference will be had to the following description and accompanying drawings, and to the appended claims in which the various novel features of the invention are more particularly set forth.

Fig. 1 of the drawings is a vertical sectional view of my improved cuspidor, this view being taken on the line 1—1 of Fig. 2.

Fig. 2 is a plan view thereof.

Fig. 3 is a fragmentary horizontal sectional view taken on the line 3—3 of Fig. 1.

Fig. 4 is a fragmentary vertical section on the line 4—4 of Fig. 3.

As here embodied my improved cuspidor comprises a cylindrical stand 10 having a flaring conical base 11. This stand is open at the top to receive a cylindrical bowl 12 which forms the cuspidor proper, this bowl having an outwardly and upwardly flared top flange 13.

The top of this bowl is normally closed by a cover 15 which engages within the flange 13, the cover being fixed on a short arm 16 which extends rearwardly through a slot 17 in the flange 13 and is pivoted between its ends as at 18 on a bracket 19 fixed to the stand 10. The rear end of the arm 16 has attached thereto the upper end of an extensible rod made up of two sections 20 united by a turnbuckle 21, the adjacent ends of the rod sections 20 being formed with respectively right and left hand screw threads.

The lower end of this rod extends through a slot 22 in the base 11 and connects to one

arm 23 of a bent lever fulcrumed between its ends as at 24 on a fixed bar 25 extending across the base 11. The other arm 26 of this lever is connected, by a slot and pin connection 27, with one end of a second lever 28 fulcrumed between its ends on the bar 25. The other end of this second lever 28 projects outwardly through a slot 29 in the base 11 and is formed as a foot pedal 30.

The fulcrum point of the lever 28 is adapted to be carried with respect to its ends, for a purpose to be presently made apparent, and to this end the fulcruming of the lever is accomplished as follows: Fixed to the bar 25 is a pin 33 which projects freely through a block 34 adjustably held in a longitudinal slot 35 in the lever and adapted to be locked to the latter by a set screw 36.

The purpose of this arrangement, as well as of making the rod 20, 21 extensible, is to variably limit the opening movement of the cover 15 when pedal 30 is depressed, so that the cover may be thrown back to substantially the angle (with respect to the vertical) of the flange 13 when the cuspidor is set at a distance from any wall, post, or vertical surface, while the backward movement may be only to substantially vertical position when the cuspidor is placed adjacent any wall or vertical position.

As shown in Fig. 1 the parts are adjusted to have the maximum backward swing of the cover 15. In this position the lever arm 23 is horizontal while the arm 26 and lever 28 incline toward one another in an obtuse V. If now the screw 36 is loosened and the turnbuckle 21 rotated to lengthen the rod of which it forms a part the lever arm 23 will assume an inclined position while the arm 26 and lever 28 will tend to straighten out to horizontal position. It will be quite apparent then, that with the lever fulcrumed in its new position by tightening screw 36 the depression of the pedal 30 to the limit allowed by the slot 29 will result in a smaller movement of the cover 15.

While I have illustrated and described a preferred embodiment of my invention it is to be understood that I do not limit myself to the precise construction herein disclosed and that various changes and modifications might be made therein without departing from the spirit and scope of the invention.

Having thus described my invention what I claim as new and desire to protect by Let-

ters Patent of the United States is as follows:

1. In a cuspidor, a hinged cover, an extensible rod connected at one end thereto, a lever fulcrumed between its ends and having said extensible rod connected to one end thereof, a second lever having one end connected to the other end of said first lever, and having its opposite end in the form of a foot-pedal, and means for varying the fulcrum point of the said lever with relation to its ends.

2. In a cuspidor, a hinged cover, an extensible rod connected at one end thereto, a

lever fulcrumed between its ends and having said extensible rod connected to one end thereof, a second lever having one end connected to the other end of said first lever, and having its opposite end in the form of a foot-pedal, and means for varying the fulcrum point of the said lever with relation to its ends, said means comprising a block freely surrounding a fixed fulcrum pin and slidable along the lever, and a screw for clamping said block to said lever.

In testimony whereof I have affixed my signature.

ANTONINA RYBICKY.
